EX

UNITED STATES PATENT OFFICE

JOHN ROGERS, OF NEW YORK, N. Y.

DESIGN FOR A GROUP OF STATUARY.

Specification forming part of Design No. 6,207, dated October 15, 1872.

To all whom it may concern:

Be it known that I, JOHN ROGERS, of the city, county, and State of New York, have invented and produced a new and original Design for a Group of Statuary, of which the following is a specification:

The nature of my design is fully represented in the accompanying photographic illustrations, to which reference is made.

The group consists of three figures, and is called "Playing Doctor." The child in the center is seated, wrapped in a blanket, and

soaking his feet in a pail of water. The girl on his right represents his mother taking care of him; while on his other side the doctor has come in with his umbrella and a bottle of medicine, and with his right hand is turning his patient's head to look at his face.

I claim as my invention—

The design for a group of figures, as shown.
JOHN ROGERS.
